Primary Examiner — Lauren Calve(74) *Attorney, Agent, or Firm* — Jonathan E. Grant; Grant Patent Service(57) **CLAIM**

I claim the ornamental design for a jewelry hanger, as shown and described.

DESCRIPTION

FIG. 1—is a perspective view of a jewelry hanger;

FIG. 2—is a front view thereof;

FIG. 3—is a back view thereof;

FIG. 4—is bottom view thereof;

FIG. 5—is a top view thereof;

FIG. 6—is a side view thereof; and,

FIG. 7—is an opposite side view thereof.

The broken lines shown represent unclaimed subject matter and form no part of the claimed design.
